UNITED STATES PATENT OFFICE.

MITCHELL D. PRICE, OF MIAMI, FLORIDA.

GARTER.

Application filed November 18, 1922. Serial No. 600,751.

To all whom it may concern:

Be it known that I, MITCHELL D. PRICE, a citizen of the United States, and a resident of Miami, in the county of Dade and State of Florida, have invented certain new and useful Improvements in Garters, of which the following is a specification.

This invention relates to garters and has for its particular object to provide a garter which may be conveniently fastened, the newly designed fastening means eliminating the necessity of the usual metallic buckle whereby possibility of the sharp edge of the buckle contacting the leg of the wearer is obviated.

A further feature of the invention resides in the constructional arrangement whereby the limb encircling member of the garter may be adjusted without the necessity of the usual slip buckle heretofore employed. Furthermore by reason of the garter construction herein illustrated the fastening or unfastening of the limb encircling member may be accomplished with facility.

The advantageous features and details of construction will be made more apparent as the description proceeds, especially when considered in connection with the accompanying drawings wherein—

Fig. 1 is a fragmentary perspective view constructed in accordance with my invention,

Fig. 2 is a similar view with the garter unfastened, and

Fig. 3 is a fragmentary plan view of a portion of the garter with the length of the limb encircling member adjusted.

Referring now particularly to the drawings wherein like reference characters indicate like parts throughout it will be noted that there is illustrated a garter pad 10 which is preferably of the shape shown in the drawings, which pad is provided with a hose engaging member 11 which can be of any desired type or construction. The pad 10 is, as in other known types of garters, formed of cloth or fabric and attached thereto as at 12 is one end of a limb encircling member 13 which is preferably, although not necessarily, formed of elastic material.

The free end of the limb encircling member 13 is formed with an enlargement or roll 14 which may be provided by rolling the end of the limb encircling member or by securing to the limb encircling member a

small metal cylinder or the like which will be enveloped and enclosed by the end of the limb encircling member and thereby securely fastened thereto. In any event a roll or enlargement 14 is provided for a purpose which will be later apparent.

Secured to the pad 10 in spaced parallel relation is a plurality of guiding and securing hook members, these members being here indicated as three in number and designated by the reference characters 15, 16 and 17. Obviously the number of these hook members as well as the distance between the same may be varied as constructional requirements dictate.

Each hook member is substantially U-shaped and is provided with a base portion 18 by which it may be secured to the pad 10, attachment of these members being accomplished in any desired manner. In this present instance the base or back of the members is perforated whereby they may be sewed to the pad 10. The other end 19 of each hook member is curved outwardly so as to facilitate the insertion of the limb encircling member therein.

The arrangement of the hook members is preferably, although not necessarily, as illustrated in the drawings, with two of the members disposed with their open side toward the bottom and with the intermediate member 16 disposed so that its open side is arranged adjacent the upper edge of the pad.

In ordinary use of the garter, the free end of the limb encircling member 13 is fastened to the pad in the manner illustrated in Fig. 1, that is, by causing the limb encircling member to engage the spaced hook members, with the enlargement or roll 14 bearing against the member 17 disposed adjacent the inner end of the pad. Obviously the limb encircling member may be easily inserted in these guiding and fastening members by slipping the edge thereof under the upturned end 19 of each member. Furthermore it will be apparent that should it be desired to increase the active length of the limb encircling member that the limb encircling member need only to engage two of the members or in fact, only one, the enlargement 14 in this instance engaging either the member 16 or the member 15 as will be immediately apparent.

On the other hand should it become neces-

sary to shorten the active length of the limb encircling member 13 this may be accomplished in the manner clearly illustrated in Fig. 3. In this figure it will be noted that the limb encircling member is looped around the innermost hook member 17 and is then again passed through the member 16 and the enlargement 14 caused to engage the outermost member 15. In any event the 10 tension upon the limb encircling member holds the same securely in place with reference to the pad 10. From the foregoing it will be clearly obvious to those skilled in this art that a garter of considerable merit 15 and utility is provided and one in which the limb encircling member may be adjustably secured in place, with the elimination however of the objectionable buckle. Furthermore in addition to the assured comfort to 20 the wearer, the arrangement affords efficient provision for a positive and secure and easily accomplished garter fastening means.

Obviously modifications will suggest themselves and to this end I hereby make reservation to make such changes in the specific details of construction as may come within the purview of the accompanying claims.

Having thus described the invention, what I claim is:

- 30 1. In a garter, a pad, a limb encircling member, an enlargement on the end of the limb encircling member and a plurality of outwardly projecting members mounted on the pad and engageable by said limb encircling member and said enlargement for guiding and securing said limb encircling member.
- 35 2. In a garter, a pad, a limb encircling member, an enlargement formed on the free end of said limb encircling member and a plurality of spaced parallel hook members secured to said pad with the open sides there-

of alternately oppositely disposed and engageable by said limb encircling member and enlargement for adjustably securing 45 the end of the limb encircling member to and parallel with said pad.

3. In a garter, an elongated pad, a limb encircling member, an enlargement secured to the free end of said limb encircling member and a plurality of hook members secured to said pad and transversely thereof, with the open ends of said hook members alternately disposed in opposite directions, said limb encircling member and enlargement 50 engaging said hook members for adjustably securing the end of said limb encircling member to said pad.

4. In a garter, a pad, the limb encircling member secured to one end of said pad, an enlargement secured to the free end of said limb encircling member and a plurality of U-shaped members secured to said pad with the open ends thereof alternately disposed in opposite directions whereby the free end 55 of said limb encircling member may be caused to engage said clips with the enlargement engaging one of said clips for the purpose described.

5. In a garter, a pad, a limb encircling 70 member secured to one end of said pad, an enlargement carried by the free end of said limb encircling member, a plurality of U-shaped members, means for securing said members to said pad, said members being 75 arranged in spaced parallel relation with the open side of said members alternately disposed in opposite directions whereby the free end of said limb encircling member and said enlargement may be caused to detachably engage said member for securing the free end of said limb encircling member to said pad.
